UNITED STATES PATENT OFFICE.

CHARLES N. SIMONSON, OF ESMOND, SOUTH DAKOTA.

DOUBLE-ACTING PUMP.

1,203,422.

Specification of Letters Patent.

Patented Oct. 31, 1916.

Application filed March 29, 1915. Serial No. 17,764.

To all whom it may concern:

Be it known that I, CHARLES N. SIMONSON, a citizen of the United States, residing at Esmond, in the county of Kingsbury and State of South Dakota, have invented certain new and useful Improvements in Double-Acting Pumps; and I do hereby declare the following to be a full, clear, and exact description of the invention, such as will enable others skilled in the art to which it appertains to make and use the same.

This invention relates to double acting air pumps, the principal object of which is to provide a pump of simple construction in which the pump piston will draw air in and force air out at each movement thereof in the pump cylinder.

Another object of the invention is to provide a pump of simple construction for forcing air at each movement of the piston, and to provide intake check valves and outlet check valves to operate alternately for taking in and forcing out air from the pump casing.

The foregoing and other objects may be attained by means of the construction illustrated in the accompanying drawing, in which the figure of the drawing is a vertical sectional view taken through a double acting pump made in accordance with this invention.

Referring to the drawing, the numeral 1 designates the pump cylinder or casing, the lower end of which is connected to a base 2 by means of exterior screw threads 3 which engage the interior screw threads of an upwardly extending boss 4 on the base. The cylinder 1 at its upper end is provided with a suitable head 5 connected by screw threads 6 inside the casing, said head 5 being provided with a stuffing box 7 and a piston rod 8 extending through the stuffing box and through the head 5. Secured to the inner end of the piston rod 8 is a piston head 9 comprising a core 9, leather packing washers 10 upon each side thereof and washers 11 of metal, said core, leather washers and metal washers being connected to the threaded end 12 of the piston rod by means of lock nuts 13 and 14, and the outer ends of the leather washers 10 projecting in opposite directions, as shown, to make an air tight joint between the piston head and the inner wall of the cylinder or casing 1. The outer end of the piston rod 8 is provided with a suitable handle 14^a.

A valve casing 15 is connected to the base 2, and an intake duct 16 extending through the base communicates with the interior of the cylinder 1 at one end while the opposite end communicates with the valve casing 15. The valve casing 15 is spaced from the outer wall of the cylinder 1, and an inclined intake nipple 17 communicates with the interior of the valve casing and is provided at its lower end with an intake port 18 controlled by a ball valve 19 having a stop 20 in the nipple. A ball valve seat 21 is formed in the valve casing 15, and a ball valve 22 is disposed above the seat 21 and is provided with a stop 23.

The cylinder head 5 is provided with an intake duct 16^a which communicates with a valve casing 24 having an inclined intake nipple 25 provided with an intake port 26 and a ball valve 27 for controlling said port, said ball valve having a stop 28 extending across the nipple 25. The nipples 17 and 25 are disposed between the valve casing and the cylinder, to be entirely out of the way so that they will not be liable to be knocked off or injured by coming into contact with some other article. In the valve casing 24 is a valve seat 29 controlled by a ball check 30 having a stop 31. The valve casings 15 and 24 are connected by an outlet tube or pipe 31^a, by means of suitable unions 32 and 33. The tube 31^a is provided with an outlet nipple 34 to which a tube is adapted to be connected for inflating a tire or for other purposes. When the piston head is moved upward in the cylinder the ball valve 19 is unseated from the port 18, and the ball 22 is seated to admit air from the valve casing 15 through the duct 16 to the cylinder. At the upper side of the piston head, the air is forced out through the duct 16^a to seat the valve 27 and to unseat the valve 30 and permit the air to be forced out through the nipple 34. At the downward stroke of the piston head, the valve 27 is unseated, the valve 30 is seated and the valve 19 is seated and the valve 22 raised from its seat to permit the air to pass out through the nipple 34, as will be obvious.

From the foregoing it will be obvious that the pump is extremely simple in construction, cannot readily get out of order, can be manufactured at low cost, and is very efficient for its purpose, since it forces air out through the nipple 34 at each movement of the piston head in the cylinder.

2
Various changes may be made in the details of construction without departing from the spirit and scope of the invention as defined in the claim.

5 What is claimed is:—

A device of the character set forth including a base, an annular flange interiorly screw threaded formed on the upper face of said base, a cylinder screw threadedly fitted in 10 said flange, a head screw threadedly fitted in the upper end of said cylinder, a central opening in said head, a stuffing box fitted in said opening, a piston rod slidably mounted through said stuffing box into said cylinder, 15 a piston head on the inner end of said rod, a valve casing secured to the upper face of said base at spaced distance from said cylinder, said base provided with an air duct communicating at one end with the cylinder and 20 its opposite end with the valve casing, a second valve casing formed on and extending from the head of the cylinder, said head and valve casing provided with an air passage

establishing communication between the cylinder and the second valve casing, said valve casings each having an inclined intake nipple provided each with a port and a ball valve, check valves in the valve casings, and a discharge pipe connected at its upper and lower 25 end to the valve casings and communicating therewith, an outlet pipe intermediate the ends of the discharge whereby upon an upward stroke of the piston rod the fluid will be discharged through the upper valve casing and out through the discharge pipe and 30 upon the downward stroke the operation is repeated only through the valve casing on the base. 35

In testimony whereof I affix my signature in presence of witnesses.

CHARLES N. SIMONSON.
